BUILDER SET

Original Filed Nov. 9, 1926

Inventor

C.I. Sweet

By *Watson E. Coleman*
Attorney

UNITED STATES PATENT OFFICE.

CLIFFORD I. SWEET, OF STERLING, ILLINOIS, ASSIGNOR TO APEX STAMPING COMPANY, OF CHICAGO, ILLINOIS, A CORPORATION OF ILLINOIS.

BUILDER SET.

Application filed November 9, 1926, Serial No. 147,278. Renewed February 4, 1929.

This invention relates to builder sets, that is, sets composed of a plurality of units or elements which may be connected to each other in a large variety of ways so as to there-
5 by form structures or toys of different characters, and the invention particularly relates to a connector whereby by certain rods or dowels may be connected to each other at different angles or in parallel relation for
10 the purpose of forming different structures.

The general object of the present invention is to provide a builder set consisting of rods and connecting elements therefor of an extremely simple character but so constructed
15 that a very large number of structural combinations may be made and which includes a connecting element so formed that the rod elements may be engaged with each other in a large number of different positions
20 and angles.

A further object is to so form this connecting element and the extremities of the rods or dowels coacting therewith that the rods or
25 dowels may be very firmly engaged with the connecting element and held rigidly in desired positions.

Other objects will appear in the course of the following description.

My invention is illustrated in the accompanying drawings wherein:-

Figure 1 is an elevation of a triangular structure formed by the elements of my builder set;

Fig. 2 is an elevation of conjoined builder set elements;

Fig. 3 is a top plan view of the structure shown in Figure 2 with the connection disks in section.

Referring to these drawings it will be seen
40 that the connecting element 10 is disk-shaped and stamped up from thin sheet metal. The central portion of the disk is formed with an aperture 11 and immediately surrounding the aperture there is a bulged or protuberant portion 12. At uniform intervals the margin of the disk is stamped up so that this margin is slightly sinuous to thereby provide a plurality of inwardly projecting, struck up, somewhat triangular ribs or protuberances
45 defining radial seats 14. These seats are defined by the side walls of the protuberant portions 13 and these side walls are tangential to the central opening of the disk so that the seats 14 are all uniform in width.

Coacting with the connecting elements 10
55 are the rods or dowels 15. These may be of various lengths and each rod or dowel is cleft or kerfed at its ends as at 16, the kerf extending diametrically across the rod.

It will be seen from Figure 3 that one or
more of these disks or connecting members 10
50 may be disposed upon a rod or dowel 15 with the rod or dowel extending through the central apertures 11 of the disk. Other rods or dowels may now be connected to the disk
55 by forcing the margin of the disk at the seat 14 into the kerf 16. The rod or dowel will now be held firmly against any oscillation or rotation between adjacent protuberant portions 13 and inasmuch as the margin
60 of the disk is inserted in the kerf, the rod will be held against movement transverse to the plane of the disk.

By using a number of these disks and engaging rods of different lengths or of any
65 desired length with the disks, a very large number of structures may be formed from these very simple elements. In actual practice each set will consist of twelve dowels or rods, of six different lengths, and thirty metal disks, and with these relatively few and simple parts, many hundreds of different structures can be built. I have not attempted
70 to illustrate all of the combinations which may be made by combining in various ways the two simple elements which form my builder set as many of these combinations
75 will be self-evident. Obviously slight variations might be made in the exact form of the disk without departing from the spirit
80 of the invention and while preferably the rods will be circular and the central opening through the disk will be circular, rods of other cross sectional form might be used and the central opening through the disk be made
85 so as to conform to the shape of the rods.

I claim:-

1. As an article of manufacture, an element for builder sets comprising a disk of thin sheet metal, the center of which is formed
100 with an aperture, the material of the disk immediately surrounding the aperture being outwardly bulged in one direction and the margin of the disk being formed with a plurality of uniformly spaced triangular protuberances defining a plurality of radial seats.

2. A builder set including a plurality of

rods having diametrically cleft ends, and connecting members for the rods, each member consisting of a disk of thin sheet metal, the disk having a central aperture and radial 5 protuberances around its margin defining a plurality of radial seats with which the cleft ends of the rods may be engaged.

3. A builder set including a plurality of rods having diametrically cleft ends, and connecting members for the rods, each member consisting of a disk of thin sheet metal, the disk being formed with a central aperture, and a protuberant portion immediately surrounding the aperture, the margin of the 15 disk being formed to provide a plurality of radially disposed, triangular protuberances

defining radial seats over which the cleft ends of the rods may be engaged.

4. In a builder set, a plurality of rods of different lengths, each rod at its opposite ends being diametrically cleft, and connecting elements for the rods each consisting of a disk of thin sheet metal, the center of the disk having an aperture snugly fitting any one of the rods, the margin of the disk being formed to provide a plurality of alternately depressed and protuberant portions defining radial seats, said seats being adapted to be inserted in the cleft of any of the rods.

In testimony whereof I hereunto affix my 30 signature.

CLIFFORD I. SWEET.
